Samuel G. Rice

UNITED STATES PATENT OFFICE.

SAMUEL G. RICE, OF ALBANY, NEW YORK, ASSIGNOR TO HIMSELF AND
HEZEKIAH DODGE, OF SAME PLACE.

IMPROVEMENT IN SASH-FASTENERS.

Specification forming part of Letters Patent No. 33,869, dated December 3, 1861.

To all whom it may concern:

Be it known that I, SAMUEL G. RICE, of the city of Albany, State of New York, have invented a new Catch for Securing Window-Sashes, which I call "Rice's rotary sash and blind holder and fastener;" and I declare the following specification, with the drawings accompanying it and forming part thereof, to be a full and perfect description of my invention.

Figure 1 represents the catch with its face-plate removed in order to show its interior mechanism. Fig. 2 represents the catch attached to a window-sash.

Similar letters in both figures denote the same parts of the apparatus.

This is an improvement upon that class of sash holders and fasteners attached to the stile of the sash and operating against the sash-frame, and is constructed as shown in Fig. 1.

A A is a shallow box, like an ordinary desk or drawer lock frame, intended to be sunk flush within the sash-stile, as shown in Fig. 2.

B is a toothed wheel, so placed that its cogs as they revolve shall project just beyond the outer edge D of the sash-frame. A bent lever L is pivoted at a, its upper limb being fitted with two teeth, forming a jaw or grip holding upon a tooth of the wheel, so as to block its movement. A spring S is so fixed to the frame as to maintain the jaw upon the tooth. The lower part of L projects backward through the frame, forming a finger-piece F, by pressing upon which the jaw can be withdrawn from the tooth and leave B free to revolve.

Upon window-sashes the frame is attached so as to bring the lever F just over one of the sash-bars, so as to permit a person about to

move the sash to place his finger under the bar and his thumb upon F, in order, by pressing them together, to unlock the wheel B. To the inner face of the window-frame, opposite the range of the wheel B, a metal rack R is secured, whose teeth are fitted to those of the wheel. The rack extends so far as is necessary to insure the appliance of the wheel for the distance the sash is to be moved.

It will be easily understood from the above description that in whatever position the sash may be the lever L will block—that is, hold—and lock it there, and that by pressing upon F and at the same time holding the sash by the sash-bar it can be moved freely a longer or shorter distance, as one pleases, when by releasing the lever the wheel will be blocked and locked immovably at that point.

The advantages that I consider this mechanism to possess over that of the catches now in use are, first, that their rolling movement makes them less liable to hitch or work foul than direct-acting teeth or bolts, which must be held back from their sockets during the raising of the sash, instead of rolling or stepping freely into them, as does the wheel or rotary catch, and, secondly, the catch operates as a roller or caster to assist the sash to free movement upward and downward.

What I claim as my invention, and desire to secure by Letters Patent, is—

The rotating catch B, in combination with the ratchet R and the stop-lever L, for the purposes set forth, and substantially as set forth in the above specification.

SAMUEL G. RICE.
